Charles Higgins, Utica, N.Y. Co. (Name)

Will of Charles Higgins

The Testator referred to in these Letters Patent making part of the same, containing a description in the words of the said Charles Higgins himself, of his improvements in the Crooking Stove.

To all to whom these presents shall come. Be it known that I, the subscriber Charles Higgins of Utica in the County of Oneida and State of New York, have invented a new and useful improvement in Stoves, and for the same to be put into common use and designated as Crooking Stoves; and that the following is a full and exact description thereof.

The front part consists of a Stove or fire place similar in form to the common open Stove with the back and sides of cast iron and a straight back at right angles with the back and nearly similar in form to the common Franklin Stove (represented in the annexed drawing A. & B.); the top of this part is an opening for a funnel or pipe to carry off the smoke when the other part is not in use, represented in the drawing A. & B. from the funnel or pipe from the bottom of the Stove an opening is made in the back from thence to pass into the hole (as shown at C.) which may be closed by a moveable stopper turned by a screw or handle on the outside (marked D.) the back is made back in one solid piece of cast iron and supports the back and sides of the Crooking part of the Stove. In the top of the part there may be set there two fire Boxes (as A. & B. & C.) and the fire and the coal coming through the opening in the back will pass under the Boxes. The oven with a door on each side (represented at C. & D.) is also constructed with plates of cast iron and a lining of a damp fire in the top that is, between the top or upper part of the oven and the top of the Stove or part in which the Boxes are set (as represented at A. & B.) the doorway or hole may be made to pass under the oven and up between the back of the Stove and side of the oven and then pass off in a funnel (A. & C. & D.) after passing over a part of the top

of the room. The flue will proceed from the top plate of the stove or fire in which the boiler is situated. The sides of the stove may easily be made of one piece of cast iron and also the hearth.

The top in which the Boilers are situated is also to be one piece. There is to be a door in this side (represented at A) opening into the fire under the Boilers and when the front part is not used a fire may be kindled over the Boilers and the oven and Boilers heated.

I shall claim as my own and not previously known or used is that part of the Stove and the arrangement by which the heat is removed from the fire place under the Boilers and to the cooking part of the Stove - & claims the construction of the back with the masonry chimney and the arrangement of the cooking part as connected with this back. The advantage of this arrangement is that the stove may be used for the purpose of cooking, or it may be used as a common open fire either over both and will answer equally well for the purpose of both - & I claim the seat.
